UNITED STATES PATENT OFFICE

ERNEST J. SANTOSUOSO, OF MEDFORD, MASSACHUSETTS

GEM MOUNTING

Continuation of application Serial No. 551,678, filed July 18, 1931. This application filed February 19, 1932. Serial No. 594,016.

My present invention relates to mountings for gems or jewels, this application being a continuation of my application Ser. No. 551,678, filed July 18, 1931.

5 The invention of the present application is particularly applicable to calibered jewels, considerable difficulty having been heretofore encountered in the assembling of such jewels or gems in a proper mounting, for 10 subsequent application to a clasp, bracelet, ring, or the like.

When utilizing a top mounting, whether of the prong or basket type, very frequently irreparable damage to the gems is caused 15 through breakage, due to the brittleness, and frequently, the softness of said gems.

An important object of the present invention, therefore, resides in the provision of a 20 mounting in which calibered gems may be assembled for best display purposes, and without likelihood of injury during the mounting process.

A further object of the present invention resides in the provision of a mounting in 25 which the gems will present their fullest degree of beauty and ornamentation.

A still further object of the present invention resides in the provision of a gem mounting which is economical to manufacture, simple to assemble, and yet strong and rugged and capable of being combined in any device desired.

The above and other objects of the invention, details of construction, combinations of parts, and advantages, will be hereinafter more fully pointed out, described and claimed.

Referring to the drawings, illustrating preferred embodiments of the present invention,

Fig. 1 is a top plan view of a gem mounting in which a series of calibered jewels are assembled according to my invention;

Fig. 2 is a longitudinal vertical sectional view on the line 2-2 of Fig. 1;

Fig. 3 is a bottom perspective view of the outer box of the mounting;

Fig. 4 is a top perspective view, partly broken away, of the internal box, tray, or gem carrier; and

Fig. 5 is a longitudinal sectional view illustrating a modified internal box.

Referring now to the drawings, for a particular description of the invention, 1 designates the internal box, tray or gem carrier, 55 provided with a plurality of apertures 2 therethrough, the walls surrounding each aperture being inclined or tapered, as at 3. I have illustrated rectangular apertures 2 as, my invention is applicable to rectangular 60 calibered stones or gems, although it will be understood and appreciated that other shapes of gems, preferably having at least one side identical with an adjacent jewel, may be utilized.

4 designates the outer box of the mounting, having the sides 5 and an inturned flange 6 on its upper surface, said flange defining a single rectangular opening 7. Depending 70 from the walls 5, at any desired points, are ears or prongs 8. When it is desired to assemble a mounting of any desired gems, stones or jewels, the set of calibered stones desired is assembled on the carrier 1, one 75 stone being positioned in each aperture 2, the tapered walls 3 cooperating with the normal tapered edges of the stones 9 to provide a firm snug seat therefor.

In carrying out my invention I preferably utilize wax to effect a temporary retention 80 of the stones 9 in the recesses 2 of the carrier 1. When the calibered stones are assembled in the carrier 1, the adjacent edges thereof are in engagement, as illustrated at 10, in 85 Figs. 1 and 2. When assembled on the tray 1, the stones and tray are then assembled with the outer box 4, until the flange 6 is in engagement with a portion of the upper surface of each stone, as clearly illustrated in 90 Fig. 2. Thereupon the prongs 8 are bent over until they engage the under surface of the carrier 1. Thus there is no stress or strain imparted to the stones themselves by the bending of the prongs 8, said prongs engaging 95 with the carrier 1 rather than with the stones 9, as would be the case in top mounting. From an inspection of Fig. 1 it will be apparent that the utilization of a single opening in the outer box permits a far more advantageous display of the gems than if said 100

opening were divided into a plurality of openings, one for each gem, as has been heretofore customary.

5 Furthermore, by eliminating the dividing bars which would be otherwise utilized, manufacture of my novel mounting is greatly simplified and the cost thereof considerably reduced.

- 10 If desired, and as illustrated in Fig. 5, I may utilize a carrier 11 having a single recess 12, provided with the beveled walls 13. In some instances, as with elongated stones as illustrated at 14, the single seat may be sufficient to properly accommodate said stones.
- 15 The outer box is identical with that illustrated in Figs. 1 to 3 inclusive. After the stones and tray have been assembled with their outer box, the application of a slight amount of heat will be sufficient to melt the retention wax, and remove the same therefrom.

20 I believe that my gem mounting, as illustrated in the present application, and providing an open housing for a plurality of calibrated stones, is novel, and have therefore claimed the same herein.

25 My novel mounting also represents a considerable saving in time over prior methods of mounting jewels or gems, and this advantage will be readily apparent to and appreciated by those skilled in this art.

30 While I have necessarily described my present invention somewhat in detail, it will be appreciated that I may vary the size, shape, and arrangement of parts within reasonably wide limits, without departing from the spirit of the invention.

35 My invention is further described and defined as follows:

40 A gem mounting comprising a box of greater length than width inclusive of side and end walls provided with inturned flanges at their upper sides, a gem carried snugly fitting within said box and having a single elongated opening therein defined by straight parallel side and end walls, a row of jewels confined between the flanges at the upper side of the box and the walls defining the opening in the carrier, the said walls being beveled to correspond to beveled bottom portions of the gems, the end jewels of the row contacting with the end walls of the box and adjacent portions of the jewels contacting with each other, whereby the jewels are effectively maintained in row disposition within the box with portions thereof exposed at the upper side of the box, and tongues on lower portions of the box bent to underlie the gem carrier to hold the latter and the gems confined within the box.

45 In testimony whereof, I have signed my name to this specification.

ERNEST J. SANTOSUOSO.
